UNITED STATES PATENT OFFICE.

EZEKIEL C. CONDIT, OF KANSAS CITY, MISSOURI.

DRY CLOSET.

SPECIFICATION forming part of Letters Patent No. 358,546, dated March 1, 1867.

Application filed September 23, 1886. Serial No. 214,341. (No model.)

To all whom it may concern:

Be it known that I, EZEKIEL C. CONDIT, of Kansas City, in the county of Jackson and State of Missouri, have invented certain new 5 and useful Improvements in Dry Closets, of which the following is a specification.

My invention relates to dry closets of that class described in Patent to I. D. Smead, No. 314,884; and the invention consists in certain improvements, hereinafter more fully described.

Figure 1 is a transverse horizontal section of a portion of a building, showing the closet with my improvements applied thereto. Fig. 2 is a longitudinal vertical section on the line xx of Fig. 1, and Fig. 3 is a transverse vertical section on the line yy of Fig. 2.

The object of my present invention is to provide means for applying a greater degree of heat to the deposits in the vault, and to cause 20 the hot air to travel a greater distance in the vault than can be when the apparatus is constructed on the plan shown in the patent referred to.

In the accompanying drawings, B represents 25 a portion of the wall of the building, and R represents the ventilating-shaft, which extends from the basement out through the roof in the usual manner. The floor of the closets is represented by the letter g , and o indicates the 30 covers of the seats, the vault C being directly underneath the same, as in the former case.

In the drawings I have shown the closets with their vaults as being built a short distance from the wall B , as I sometimes find it desirable, though in cases where it is more convenient they may be built up against the wall B , their location depending on circumstances— 35 as, for instance, whether the dry closet is to be applied to a building already erected, or is to be put in when the building is being built, my 40 improvements being applicable in either case.

In the patent before referred to the vault was supplied with air drawn from the various rooms of the building, and which of course was somewhat reduced in temperature by the time it 45 entered the vault, through which it was drawn direct to the ventilating-shaft, the air passing but once through the vault and in one direction only.

As shown in Figs. 1 and 2, I take the air for

the vault directly from the exterior of the building through an opening, K , provided for that purpose; and in a suitable chamber at that end of the vault I locate a furnace or heater, A , by which the air is heated to any degree desired. Within the vault C , I locate a metallic partition or plate, L , as shown, whereby the vault is divided into two parts or ducts, d and d' , the one over the other, as shown in Figs. 2 and 3, the plate L being directly under the 55 seats, so the deposits will fall thereon and be retained on said plate. This plate L is enough shorter than the vault to leave at the end farthest from the heater A an opening, I , as shown in Figs. 1 and 2, for the passage of the air from the lower duct, d , up into the duct d' , as indicated by the arrows in Fig. 2. At the end nearest the heater A the upper duct, d' , is closed by a plate or partition, e , as shown in Fig. 2, and at that end this duct d' is connected with 60 the ventilating-shaft R by a pipe, v ; or if the vault be built directly against the wall B , so as to abut against the shaft R , it may 65 simply open into the shaft without any pipe, the only requisite in that particular being that it shall be so connected to the shaft R as to insure the passage of the air from the duct d' into the ventilating-shaft. This ventilating-shaft is always provided with means for heating it 70 sufficiently to rarefy the air therein, and thus 75 insure a good upward draft. In this case I have shown a smoke-flue, T , built up alongside of the ventilating-shaft, into which the smoke from the heater A is conducted by a pipe, S , as shown in Fig. 1, the heat from which answers 80 this purpose, though any other method may be adopted, if preferred, this, however, being 85 the most convenient, inasmuch as there must be a flue for carrying away the smoke and gases of the heater or furnace A .

At the end of the vault farthest from the heater I provide an opening with a door, K' , as shown in Figs. 1 and 2, to afford access to the vault for the removal of the dried deposits, when required, this door, however, being kept 90 closed at all other times.

I would remark that the plate L may be provided with perforations sufficient to permit whatever liquid matter there may be to drain through and fall upon sand, t , or other absorb- 95 100

ent in the bottom of the vault, though this is not a necessity.

The operation of the apparatus thus constructed will be readily understood. The air entering at the opening K will be heated by the heater A to any degree desired, and will pass thence through the lower duct, d, thereby heating the plate L and the deposits thereon, at the same time absorbing or drying up whatever moisture there may be in the bottom of said duct, and, passing thence up through the opening I into the upper duct, d', will pass back through the same in direct contact with the deposits on the plate L, and from thence into the shaft R, and out through the same into the atmosphere above the roof of the building. By these means I apply air at a much higher temperature and pass it twice through the vault, instead of once, as heretofore, thus greatly hastening the drying or desiccating process. By taking the air entirely from the exterior of the building, and having the vault entirely disconnected from ventilating ducts or passages of the rooms within the building, I prevent the possibility of the air which enters the vault from penetrating any of the rooms in case of a reversal of the currents, or any accident of the kind.

I am aware that a patent has been granted in which there is shown a metal box under the seats of an ordinary privy, with a fire-grate located outside of the same, in which it is proposed to build a fire at intervals for the purpose of drying or consuming the deposits, and that lamps and other appliances have been described as applied to commodes or portable devices for use in dwellings, and therefore I do not claim any of them. Neither do I claim a dry closet having a current of air drawn through its vault and out through a shaft; but

What I claim as my invention is—

The combination, in a dry closet, of the vault C, provided with the transverse plate or partition L, with the opening or passage I at one end and the heater A and air-inlet K at the opposite end, the upper portion or duct, d', of said vault being connected to the ventilating-shaft R, all being constructed and arranged to operate substantially as and for the purpose set forth.
